UNITED STATES PATENT OFFICE.

WILLARD F. RICHARDS, OF BUFFALO, NEW YORK.

DESIGN FOR A THRESHOLD-PLATE.

SPECIFICATION forming part of Design No. 23,390, dated June 19, 1894.

Application filed May 4, 1894. Serial No. 510,112. Term of patent 14 years.

To all whom it may concern:

Be it known that I, WILLARD F. RICHARDS, citizen of the United States, residing at the city of Buffalo, in the county of Erie and State of New York, have invented and produced a new and original Design for Threshold-Plates for Railway-Cars, of which the following is a specification.

This design relates to the ornamentation of the threshold plates which are employed in passenger cars, for covering the joint between the horizontal wing or rearward extension of the buffer and the floor of the car platform.

The design is illustrated in the accompanying drawings, in which—

Figure 1 is a plan view of a threshold plate embodying my design. Fig. 2 is a fragmentary view thereof, on an enlarged scale. Figs. 3 and 4 are cross sections of the same in lines 3—3 4—4 Fig. 1, on an enlarged scale.

Like letters of reference refer to like parts in the several figures.

The leading feature of my design consists in two plain depressed panels D arranged

upon the end portions of the oblong threshold plate and a depressed oblong field A arranged upon the central portion of the plate and enclosed by a raised border B, the surface of which is ornamented with a diaper pattern composed of pyramidal figures of a diamond or lozenge-shaped outline. The longitudinal portions of this border extend to the adjacent edges of the threshold plate and the end portions thereof are pointed or V-shaped. A series of holes c extend along one of the longitudinal margins of the threshold plate. Each of the plain end panels D is bounded by a raised rib or bead d.

What I claim is—

The design for a threshold plate herein shown and described.

Witness my hand this 29th day of December, 1893.

WILLARD F. RICHARDS
